UNITED STATES PATENT OFFICE.

PAUL R. HARSH, OF TOLEDO, OHIO.

KEYHOLE-ILLUMINATING APPARATUS.

1,191,783.

Specification of Letters Patent. Patented July 18, 1916.

Application filed June 11, 1915. Serial No. 33,551.

To all whom it may concern:

Be it known that I, PAUL R. HARSH, a citizen of the United States of America, residing at Toledo, in the county of Lucas and State of Ohio, have invented new and useful Improvements in Keyhole-Illuminating Apparatus, of which the following is a specification.

This invention relates to improvements in apparatus for illuminating the keyholes of doors so that the keyholes may be quickly and conveniently located at night when it is desired to insert the key therein.

In carrying out the present invention, it is my purpose to provide a keyhole illuminating apparatus whereby the keyhole may be quickly and conveniently illuminated when the door is latched closed and where- 20 nating the keyhole will be automatically broken at a point remote from the hand switch when the door is in open position, thereby preventing waste of current in the repeated operation of the switch.

It is also my purpose to provide apparatus of the class described which will embrace the desired features of simplicity, efficiency and durability, which may be installed and maintained at small cost which 30 will operate efficiently and effectively for its intended purpose and wherein the component parts will be so arranged and correlated as to reduce the possibility of derangement to a minimum.

A further object of my invention is the provision of a keyhole illuminating apparatus which may be used in connection with the door bell and burglar alarm apparatus so that the door bell may be operated inde- 40 pendently of the illuminating apparatus, when the burglar alarm will be put in operation in the event of a person endeavoring to effect an unlawful entrance into the house.

With the above and other objects in view, the invention consists in the construction, combination and arrangement of parts hereinafter set forth in and falling within the scope of the claims.

In the accompanying drawings; Figure 1 is a fragmentary front elevation of a door equipped with keyhole illuminating apparatus constructed in accordance with the present invention. Fig. 2 is a fragmentary 55 horizontal sectional view through the door and door jamb showing the relative posi-

tions of the keyhole and lamp. Fig. 3 is an enlarged front elevation of the door showing the various circuit connections, parts being broken away and other parts 60 shown in section. Fig. 4 is a similar view showing a modified form of the invention. Fig. 5 is a sectional view on the line 5—5 of Fig. 4. Fig. 6 is a diagrammatic view showing the various circuit connections. Fig. 7 is a fragmentary edge view of one 65 of the side stiles of the door frame. Fig. 8 is a fragmentary longitudinal sectional view through the door knob and escutcheon plate, parts being shown in elevation. 70

Referring now to the drawings in detail, 1 designates a door jamb and 2 the door hinged at one edge to one stile of the jamb and capable of swinging movement to open and closed positions. The inner surface of 75 the remaining side stile of the door jamb, at a point adjacent to the center thereof, is formed with a recess and secured to the inner surface of such side stile at the recess is a plate 3 formed with openings 4 and 5 80 spaced apart vertically. The side edge of the door adjacent to the plate 3 is formed with a mortise and disposed within such mortise is a lock 6 of appropriate construction and the latching bolt of the lock 6 is 85 adapted to enter the opening 4 to latch the door in closed position, while the opening 5 is designed to receive the locking bolt so that the door may be locked in closed position. Secured to the opposite sides of the door and 90 formed with keyholes alining with each other and with the keyhole in the casing of the lock 6 are escutcheon plates 7 while formed in the escutcheon plates above the keyholes therein are circular openings alining with each other and with the opening in the barrel controlling the latching bolt and passed through these alining openings is a shank 8 having the opposite ends thereof equipped with knobs 9 respectively 95 100 whereby the barrel may be rotated to retract the latching bolt.

Formed in the side stile of the door jamb adjacent to the plate 3 and disposed in proximity to the keyhole of the lock is a recess 105 10 and disposed within the recess 10 is an electric lamp receptacle 11 secured within the recess by means of a plate 12 fastened to the side stile of the jamb and formed with an opening concentrically of the receptacle. 110 Passed through this opening and threaded into the receptacle is the body of an electric

lamp bulb 13, while secured to the wall of the opening in the plate 11 and partially surrounding the bulb 13 is a reflector 14 acting to throw the light rays from the bulb 5 toward the keyhole. Secured to the inner surface of the door jamb adjacent to the upper end thereof is a contact 15 and adapted to engage the contact 15 is a contact finger 16 carried by the adjacent edge 10 of the door 2 and designed to engage the contact 15 when the door is in closed position. Leading from the contact finger 16 is a conductor 17 terminally connected with a binding screw 18 carried by the escutcheon 15 plate upon the outer side of the door, while seated within a recess formed in the outer end of the knob on the outer side of the door is a push button switch 19. One terminal of the push button switch 19 is grounded 20 upon the adjacent escutcheon plate by means of a wire 20, while the remaining terminal of the switch 19 is connected with the adjacent door knob as at 21. In accordance with my present invention, the outer door knob 25 and the shank 8 are insulated from the outer escutcheon plate by means of insulating bushings 22. Secured to the rear face of the plate 3 and extending into the recess in the door jamb behind the opening 4 is a 30 contact plate 23 adapted to be engaged by the latching bolt of the lock 6 when the door is in closed position. Leading from the contact plate 23 is a conductor 24 terminally connected to one side of the receptacle 11 35 and from the remaining side of the receptacle 11 leads a conductor 25, while from the contact 15 leads a conductor 26. By means of this construction, it will be seen that when the conductors 25 and 26 are connected with 40 a battery or other source of electrical energy and the door in closed position, the circuit thus formed will be opened at the push button switch and may be closed when the push button switch is depressed, thereby energizing 45 the filament of the lamp bulb 13 so that the rays of light will be projected toward the keyhole to illuminate the latter to facilitate the insertion of the key therein. When the push button switch is closed, current 50 flows through the established circuit as follows; from one side of the battery, through the conductor 26, the contact 15, contact finger 16, conductor 17, the escutcheon plate, the ground wire 20, through the push button switch 19, the door knob, the shank 8 carrying the knob, the latching bolt, the contact plate 23 engaged by such bolt, the conductor 24, the lamp, and back to the battery by way of the conductor 25. 32 designates 55 a battery having the opposite sides thereof connected with the terminals of the conductors 25 and 26 respectively.

34 designates a relay controlling a local burglar alarm circuit 38 and leading from 60 one terminal of the winding of the relay 34

is a conductor 33 including a suitable controlling switch 28 and terminally connected to the conductor 26, while leading from the remaining terminal of the winding of the relay 34 is a conductor 35 terminally connected with one contact of a pair 36 located in the keyhole of the lock and spaced apart therein. The remaining contact of the pair 36 is connected by way of a conductor 37 with the other side of the battery 32. Thus, 70 it will be seen that when a key is inserted in the keyhole, the contacts of the pair 36 will be bridged, thereby closing the circuit of the relay 34 with the effect to energize such relay so that the burglar alarm circuit 38 will be 80 closed, current flowing through the relay circuit as follows; from one side of the battery 32, through a portion of the conductor 26, the conductor 33, and the closed switch 28 therein, the relay 34, the conductor 35, the 85 bridged contacts 36, and the conductor 37, back to the battery.

39 designates an electric bell and one side of the bell 39 is connected with the conductor 33 between the switch 28 and the battery 32 90 by way of a conductor 40, while the remaining side of the bell 39 is connected with one side of a push button switch 41 located upon the outer side of the door jamb and the remaining terminal of the push button switch 41 is connected with the other side of the battery by way of a conductor 42.

In the modified form of my invention illustrated in Fig. 4, I have shown a form of push button detachably connected with the outer knob. In the present instance, the push button comprises a collar 43 of insulating material surrounding the hub of the knob and secured thereto by means of a set screw 44, and a curved leaf spring 45 disposed upon the periphery of the collar 43 and having one end secured to the collar and the remaining end portion disposed over a radial opening 46 formed in the collar and secured to this end of the leaf spring is a stem 47 having the inner end extending through the opening 46 and adapted to be forced into engagement with the knob shank or spindle. The spring strip 45 is grounded upon the adjacent escutcheon plate so that when the stem 47 is depressed to engage the knob shank or spindle the circuit of the lamp will be closed, thereby energizing the lamp. 110

While I have herein shown and described certain preferred forms of my invention by way of illustration, I wish it to be understood that I do not limit or confine myself to the precise details of construction herein described and delineated, as modification and variation may be made within the scope of the claims without departing from the spirit of the invention. 120

I claim:

1. In keyhole illuminating apparatus, a

5 lamp disposed in proximity to the keyhole, an electric circuit including said lamp, a push button switch in said circuit carried by the door knob on the outer side of the door whereby the circuit may be closed to energize said lamp, door operated means closing said circuit at a point remote from said push button switch and adapted to open the circuit in the movement of the door to open 10 position, said circuit including the latching bolt of the door, and a plate carried by the door jamb in the path of movement of the latching plate, whereby the circuit will be completed when the door is closed and 15 latched.

2. In apparatus of the class described, a

lamp disposed in proximity to the keyhole of the door, an electric circuit including said lamp, a switch in said circuit adjacent to the keyhole whereby the circuit may be 20 closed to energize said lamp, an alarm circuit controlling relay keyhole contacts connected in circuit with said relay and adapted to be bridged by the key to energize the relay, and a bell, and a push button switch 25 connected in series with each other.

In testimony whereof I affix my signature in presence of two witnesses.

PAUL R. HARSH.
